UNITED STATES PATENT OFFICE

171,506

COMBINATION FOLDING CAMP, BOAT, AND LAWN CHAIR

Floyd A. Laird, Bend, Oreg.

Application June 8, 1953, Serial No. 25,380

Term of patent 14 years

(Cl. D15—1)

To all whom it may concern:

Be it known that I, Floyd A. Laird, a citizen of the United States, residing at Bend, in the county of Deschutes, State of Oregon, have invented a new, original, and ornamental Design for a Combination Folding Camp, Boat, and Lawn Chair, of which the following is a specification, reference being had to the accompanying drawing, forming a part thereof, in which:

Figure 1 is a perspective view of a combination folding camp, boat, and lawn chair, in erected condition, showing my new design; and

I claim:

The ornamental design for a combination folding camp, boat, and lawn chair, as shown.

FLOYD A. LAIRD.
